UNITED STATES PATENT OFFICE.

SWAN H. NORD, OF SEATTLE, WASHINGTON.

SELF-DRAINING OIL CAN.

Application filed February 2, 1928. Serial No. 251,288.

My invention has particular reference to improvements in oil cans of the type commonly employed in making deliveries of lubricating oil by wholesalers to retailers from trucks, and its objects, generally stated, are, to provide an annular member disposed in the neck of such a can and adapted, when the can is inverted, to permit the residue of oil remaining in the body of the can after 10 pouring to drain into the detachable top of the can, thus making it easy to save for the retailer such residue, which, under usual conditions, would be a loss to him; and, to afford through said member, when the can 15 is in an upright position, a receptacle, having a drainage port, into which any oil remaining in the top, after said residue has been poured therefrom, may drain back into the body of the can, thereby keeping said top 20 as free as possible from accumulations of oil.

Other objects may appear as the description of the invention progresses.

In the accompanying drawing—

Figure 1 is a front elevation of the device 25 as applied to such a can, the can being slightly modified to best meet the requirements of the device, and certain portions being shown in cross section and broken away;

Fig. 2, a view of the same in an inverted 30 position, the body of the can being broken away; and,

Fig. 3, a cross section drawn on the line 3—3, of Fig. 2.

Referring more particularly to the drawing, 1 designates the cylindrical body of 35 the can, from which I prefer to eliminate the corrugations commonly found in standard cans of this type, 2 the neck and 3 the handle, of usual construction. The bottom 40 of the can 4 is made to bulge inwardly, which permits a handle 5 to be secured to its exterior surface and still be disposed within the base portion 6, as indicated in Fig. 1. The detachable top of the can is 45 provided with a body portion 7, which telescopes within the neck and is also of usual construction, its outer rim portion 8, however, being somewhat wider than the similar part found in the conventional can, the purpose 50 of which will be presently described.

The annular member, heretofore referred to, consists of a cylindrical portion 9 secured to the inner circumference of the neck and adjacent the body of the can, having its 55 inner edge section beveled, as at 10. An integral, inwardly directed shoulder section

11 extends from the portion 9 throughout its diameter and terminates in a second integral and cylindrical portion 12, of smaller diameter than the first-named portion, designed 60 to extend within the detachable top and in spaced relation therewith, when said top is in closed position, as shown in Fig. 1. Said member is provided with a pair of oppositely disposed and bore-like openings which serve 65 as drainage ports for oil and are denoted as 13, said ports being located in the shoulder and adjacent the first-named cylindrical portion.

In delivering oil from the can, obviously, 70 after the top is removed, the handle 5 affords convenient means for tilting the can, in pouring the contents. By reason of its viscosity, a certain amount of oil will be left in the can after pouring, which amount I have found 75 by experiment to be approximately three-fourths of a pint in a standard can of five gallons capacity. To recover the residue thus left, the top of the can is then put in place, and the can inverted as shown in Fig. 80 2, when said residue, as is obvious, will drain into the can top, as at 14, the beveled section 10 serving to facilitate the flow of the oil through the annular member, and the smaller end of said member directing the 85 flow into said top. The top is then removed from the can by the user placing either foot on the rim 8—which is enlarged for this purpose—and pulling the remainder of the can away from the top, through the handle 90 5. The residue of oil accumulated in the top and thus saved for the purchaser may be poured out, the top replaced and the can returned to its upright position. As it may be noted, the portion 12 of the annular member 95 has a diameter reduced in size relative to the inner circumference of the adjacent portion of the neck, thus forming, in co-operation with the shoulder 11 and when the can is in an upright position, a channel-like and circumferentially extending receptacle 15 for oil which may drain from the top, and then be discharged through the drainage ports 13 into the body of the can. The portion 12, as is evident, will also permit 100 drippings of oil from the top to be deposited in said body. In this manner the top is kept relatively free of oil and clean for handling purposes.

The device, exceedingly simple in construction as it is, may be further simplified by dispensing with the handle 5 and the en-

larged rim 8, and still be operative, as will be obvious to those skilled in the art, and other changes in and modifications of the construction described may be made without departing from the spirit of my invention or sacrificing its advantages, hence I ask that I be not confined to the specific structure set forth.

I claim:

- 10 1. A self-draining oil can, comprising a container, an inwardly curved bottom member disposed above the base of the container, a handle secured to the member and located within the base, a neck for the container terminating in a mouth, a detachable top telescopically engageable with the neck, a laterally projecting rim for the top, an annular member located within the neck and extending circumferentially thereof, having one end disposed adjacent the container, its other end being reduced in diameter and extending within said top when the top is in closed position, said member being apertured to provide a discharge port for oil.
- 15 2. A self-draining oil can, comprising a container, a neck for the container terminating in a mouth, a combined top and drainage receptacle for the container telescopically engageable with the neck, an annular member located within the neck and extending circumferentially thereof, one end of said member communicating with the container and the other end reduced in diameter and extending within the top when the top is in closed position, said member being apertured to provide a discharge port for oil.
- 20 3. A self-draining oil can, comprising a body portion, a neck terminating in a mouth, a top slidably engaged within the neck, an annular member secured within the neck, having an end portion projecting into and disposed in spaced relation with the top when said top is in closed position, and a drainage port in the member, said member being adapted to drain oil from the body portion into the top when the can is in an inverted position, and to receive and drain oil from said top into the body portion when the can is in an upright position.
- 25 4. In a self-draining oil can having a body portion, a neck portion terminating in a mouth, and a top telescopically engageable

with the neck and mouth, an annular member fixedly secured within the neck and adjacent the body portion, the same being inwardly beveled at its end disposed adjacent the body portion, its other end being reduced in diameter and extending within said top when the top is in closed position, and a discharge port for oil in the member, said member adapted to drain oil from the body portion into the top when the can is in an inverted position, and to receive and drain oil from said top into the body portion when the can is in an upright position.

5. In a self-draining oil can having a body portion, a neck portion and a detachable top telescopically engageable with the neck portion, an annular member fixedly secured within the neck, having an end portion reduced in diameter and projecting into and spaced away from the top when said top is in closed position, said member being adapted to drain oil from the body portion into the top when the can is inverted and to provide, in cooperation with the surface of the neck adjacent said end portion, a drainage receptacle for the top when the can is upright, the member being apertured to afford a port for discharging oil from the receptacle into the body portion.

6. In a self-draining oil can having a body portion, a neck portion and a detachable top telescopically engageable with the neck portion, a member secured to the neck portion and projecting into and spaced away from the top when said top is in closed position, adapted to drain oil from the body portion into the top when the can is inverted and to afford a drainage receptacle for the top when the can is upright, the member being apertured to provide a port for discharging oil from the receptacle into the body portion.

7. In a self-draining oil can having a body portion, a neck portion and a detachable hollow top engageable with the neck portion, an annular member secured to the neck portion and extending into the top when said top is in closed position, adapted to drain oil from the body portion into the top when the can is inverted and to provide a drainage receptacle for the top when the can is upright.
